(57) **CLAIM**

The ornamental design for a multi-camera mobile device, as shown and described.

DESCRIPTION

FIG. 1 is a front view of a multi-camera mobile device, showing our new design.

FIG. 2 is a rear view thereof.

FIG. 3 is a left side view thereof.

FIG. 4 is a right side view thereof.

FIG. 5 is a top view thereof.

FIG. 6 is a bottom view thereof.

FIG. 7 is a top-left-front perspective view thereof.

FIG. 8 is a bottom-right-front perspective view thereof.

FIG. 9 is a bottom-right-rear perspective view thereof; and, FIG. 10 is a top-left-rear perspective view thereof.

The broken lines are directed to environment and are for illustrative purposes only. The broken lines form no part of the claimed design.

The “360° intel” logo in FIGS. 2, 9, and 10 forming part of the disclosure includes a trademark. Specifically, Intel® is a registered trademark of Intel Corporation.

1 Claim, 8 Drawing Sheets
